UNITED STATES PATENT OFFICE.

HARRY THORIN, OF MONSON, MASSACHUSETTS.

RULE POCKET.

Application filed April 3, 1926. Serial No. 99,652.

This invention relates to tool holders and has for its object the provision of a novel metallic holder adapted for use by mechanics and others for the purpose of holding in place a folding or other rule so that it will not drop out of the pocket when the user stoops over or moves about in other ways necessitated by the carrying out of his work.

An important object is to provide a holder 10 of this character embodying a spring forming a part thereof which frictionally bears against the rule and holds it firmly so that it cannot possibly drop out but which will yet permit the rule to be withdrawn when 15 such is actually desired.

Another object of the invention is to provide a holder of this character which is provided with means whereby it may be quickly and easily engaged upon or disengaged from 20 a pair of overalls or other garment, the device being provided with peculiar holding means which will obviate any necessity for sewing it in place.

A further object is to provide a device 25 of this type provided with a separate compartment for the reception of a pencil, retaining means being located therein for frictionally gripping the pencil and holding it firmly against accidental dropping out.

An additional object is to provide a device of this character which will be simple and inexpensive in manufacture, easy to install or apply, positive in action, efficient and durable in service, and a general improvement in the art.

With the above and other objects and advantages in view, the invention consists in the details of construction and the arrangement and combination of parts to be hereinafter more fully described and claimed, and illustrated in the accompanying drawings, in which:

Figure 1 is a perspective view of the device in applied position upon overalls, a ruler being held in the device,

Figure 2 is a vertical longitudinal sectional view taken at substantially the center,

Figure 3 is a detail cross section taken on the line 3—3 of Figure 2,

Figure 4 is a perspective view showing the retaining member and the device itself in detached relation, and

Figure 5 is a detail perspective view show-

ing the back member applied against the underside of overalls or another garment. 55

Referring more particularly to the drawings, I have shown the device as comprising an elongated receptacle 10 which may be constructed of any suitable material but preferably metal and which may, in actual 60 practice, be formed from a single sheet of blank cut and bent to the desired shape. This receptacle 10 is of course of the proper size to receive a folding rule or the like indicated at A though is of course conceivable that it might be constructed for the purpose of holding some other object other than a ruler. The top of this receptacle is open as indicated at 11 whereas the bottom is closed by a preferably curved wall 12 70 forming a continuation of the back and front as clearly indicated in the drawings. At the upper end the back wall is formed with an extension 13 which is bent outwardly and downwardly as clearly indicated 75 so as to be capable of engagement over the edge of a pocket or over a retaining strip or plate 14, of metal, adapted to be disposed against a garment indicated at B. The manner of securing the device will 80 be hereinafter explained more fully.

Located within the receptacle 10 is a partition 10^a defining separate compartments 10^b and 10^c, within the former of which is arranged an elongated leaf spring 15 which 85 has its free end preferably curved as indicated at 16 so as to be capable of sliding movement along the back wall of the container or receptacle. The other end of this spring passes through slots 17 in the back 90 wall and is then secured in place as for instance by means of a suitable rivet 18 which likewise passes through the back wall. The plate member 14 is formed centrally with an opening 19 for the accommodation of this 95 rivet 18 as clearly indicated. It is intended that the folded rule A be inserted within the compartment 10^b whereupon the spring 15 will of course be compressed and will bear frictionally against the rule for the purpose 100 of holding it firmly in place and preventing it from dropping out in case the user stoops over or moves about in some other similar manner.

The back of the compartment 10^c is 105 equipped with a similarly mounted spring

15^a. A pencil B may be carried in this compartment and owing to the provision of the spring it is evident that the pencil will be retained in place in the same manner as the folded rule.

For securing the device in place, use is made of an elongated metallic back plate member 20 adapted to be disposed against the rear or underside of the garment, this 10 plate member carrying a pair of outstanding studs 21 adapted to be passed through suitable holes 22 in the garment and through holes 23 in the end portions of the strip or plate 14. These stud members 21 carry outwardly spring pressed catches 24 which have inclined outer surfaces 25 and angular shoulders 26 so that when the plate member 14 is engaged upon the studs 21 the latches 24 will move inwardly until the member 14 has 20 passed to a point firmly against the garment whereupon the latches 24 will spring outwardly, the shoulders 26 thereof operating to prevent the plate member 14 from being disengaged. As stated above, the portion 13 25 of the receptacle engages over the strip or plate 14 and as the rivet 18 is accommodated within the hole 19, there is no likelihood of the container itself becoming displaced.

From the foregoing description and a 30 study of the drawings it will be apparent that I have provided a simply constructed and inexpensive device for the purpose specified and one which will be a great convenience to mechanics and other persons inasmuch as it will prevent dropping out and loss of their rules. It is believed that the construction, operation and advantages will be readily apparent to one skilled in the art 35 without further explanation.

While I have shown and described the preferred embodiment of the invention, it should be understood that I reserve the right to make such changes in the form, construction and arrangement of parts as will not deviate 40 from the spirit of the invention or the scope of the subjoined claims, as for instance

it is immaterial whether the size be such as to carry a rule of the two-foot or six-foot type. Other changes or variations may of course suggest themselves.

50

Having thus described the invention, I claim:—

1. A rule holder comprising a receptacle having an open top and a closed bottom, and provided at the upper end of its back with an overhanging flange member, in combination with a pair of metallic strips adapted for disposition against the under and front sides of a garment, and securing members carried by the strips for holding them in place, the overhanging flange member being detachably engaged over and upon said pair of strips.

2. A rule holder comprising a receptacle having an open top and a closed bottom, and provided at the upper end of its back with an overhanging flange member, in combination with a pair of metallic strips adapted for disposition against the under and front sides of a garment, and securing members carried by the strips for holding them in place.

3. A rule holder comprising a receptacle having an open top and a closed bottom, and provided at the upper end of its back with an overhanging flange member, in combination with a pair of metallic strips adapted for disposition against the under and front sides of a garment, and securing members carried by the strips for holding them in place, the securing means for the strips including studs projecting forwardly through the garment and carried by the rear plate member, said studs being equipped with outwardly spring pressed latch members having inclined outer edges and rectangular shoulders, said latch members being insertable through openings in the forward plate member and to be retained thereby for preventing the parts from disassociation.

In testimony whereof I affix my signature.

HARRY THORIN.
